UNITED STATES PATENT OFFICE.

ROBERT I. McNAUGHTON, OF IRON MOUNTAIN, MICHIGAN.

BAG-HOLDER BRACKET.

Application filed May 2, 1923. Serial No. 636,215.

To all whom it may concern:

Be it known that I, ROBERT I. McNAUGHTON, a citizen of the United States, residing at Iron Mountain, in the county of Dickinson and State of Michigan, have invented certain new and useful Improvements in Bag-Holder Brackets, of which the following is a specification.

This invention relates to bag holder bracket, and has for one of its objects to improve the construction and increase the efficiency and utility of devices of this character.

With these and other objects in view, the invention consists in certain novel features of construction as hereinafter shown and described and then specifically pointed out in the claim, and in the drawings illustrative of the preferred embodiment of the invention.

Figure 1 is a front elevation, and

Fig. 2 is a side elevation, of the improved device.

Fig. 3 is a front elevation, enlarged, of one of the supporting brackets.

Fig. 4 is a side view of the member shown in Fig. 3, partly in section.

Fig. 5 is a section on the line 5—5 of Fig. 4, looking in the direction of the arrow.

The improved device includes a standard formed of a tubular lower portion 10 and an upper portion 11, which may also be tubular, and slidably in the lower portion and held in adjusted position by a set screw 12 or the like.

The tubular standard portion 10 is stepped in a foot member 13, and the latter in turn attached to a base plate 14. The member 14 is extended in all directions from the base 13 and provided at each side with a carrier wheel 15 located at the rear of the platform as shown. The platform is turned downwardly at its front side as at 15^a and then extended forward as at 16 in a plane parallel with the platform and in alinement with the lowest point of the wheels, so that the bottom of the extended portion 16 rests upon the ground or floor and, while acting as a "third leg" to support the device also constitutes a bag rest as indicated in dotted lines in Fig. 2.

A bail like member 17 is attached by its ends to the sides of the member 14 at its front, as shown, to provide a further support for the lower portion of the bag.

By this means, the improved device may

be readily moved from place to place by slightly elevating the portion 16 to enable the bearing wheels to be utilized.

Attached to the upper end of the upper part 11 of the standard and extending transversely thereof, is a head member 18, which may be of wood, and attached to the head member at each end, is a bracket device, but as the bracket devices are alike, the description of one will suffice for both.

Each bracket device is formed with a vertical portion 19 and a horizontal portion 20, the portion 20 having a depending lip 21 bearing over the upper edge of the member 18, and the portion 19 perforated to receive a rivet or the like 22 by which it is secured to the member 18.

The members 19 and 20 are coupled by a brace web 23, and the horizontal portion 20 is provided at its rear with a guideway or housing 24 having a polygonal shaped passage 24^a extending longitudinally therethrough. The opposed side walls of this passage have formed therein recesses 25, and in each recess is secured, at one end, a spring 26 curved and adapted to project outwardly into the passage, in opposed relation to the spring in the opposite recess.

The bag supporting portion of the device 85 comprises a metal rod having the side legs 27 and 28 and curved connecting portion 29. The legs 27 and 28 extend in parallel relation and are of the same size as, and are slidably received respectively in, the passages 24^a of the housing 24, as shown in Figures 1, 2 and 3, and frictionally engaged by the springs 26.

The upper faces of the portions 20 constitute rests for the sides 28 of the U-shaped bag holding member, and coat with the guide members 24 to relieve the bag support largely from downward strain under the weight of the loaded bag.

The springs will be of sufficient strength 100 to hold the bag supporting members against accidental displacement, or from normal strains to which they will be subjected when holding the bag in filling position, but will yield to abnormal strains to enable the holder to be adjusted to fit different sized bags, or to be removed altogether.

By forming a standard in the two sections, telescopically united, the holder members 27, 28 and 29, may be adjusted vertically to suit bags of different heights.

The improved device is simple in con-

struction, and can be manufactured wholly of metal except the portion 18 which may also be of metal if desired.

The preferred embodiment of the invention is disclosed in the drawings and set forth in the specification, but it will be understood that modifications within the scope of the claim may be made in the construction without departing from the principle of the invention or sacrificing any of its advantages.

Having thus described the invention, what is claimed as new is:—

15 A bracket for the purpose set forth comprising, a substantially elongated relatively wide, flat horizontal portion, a vertical portion depending from the under side and adjacent one end thereof, a reinforcing web ex-

tending longitudinally of the center of and connecting the back of said vertical portion 20 with the under face of the rear of said horizontal portion, means to provide an integral longitudinally extending housing upon the rear of said horizontal portion, having a polygonal longitudinally extending passage 25 therethrough open at each end, said housing further having the inner side walls provided with opposed recesses, and a spring secured at one end in each recess and having a curved portion normally projecting into 30 said passage to engage and securely grip the sides of a member extending through the passage.

In testimony whereof, I affix my signature hereto.

ROBERT I. McNAUGHTON.
